(57) **CLAIM**

The ornamental design for a iron-type golf club head, as shown and described.

DESCRIPTION

FIG. 1 illustrates an angled, rear perspective view of a golf club head that shows a cavity pad and a perimeter weight; FIG. 2 illustrates a rear perspective view of a golf club head that shows a cavity pad and a slight concave shaped perimeter weight;

FIG. 3 illustrates an angled, rear perspective view of a golf club head that shows a cavity pad and a perimeter weight;

FIG. 4 illustrates an angled, bottom perspective view of a golf club head that shows a cavity pad and a perimeter weight;

FIG. 5 illustrates an angled, rear perspective view of a golf club head that shows a cavity pad and a slight concave shaped perimeter weight;

FIG. 6 illustrates an angled, side perspective view of a golf club head that shows a cavity pad and a perimeter weight;

FIG. 7 illustrates a top perspective view of a golf club head that shows a top portion of a perimeter weight;

FIG. 8 illustrates a rear perspective view of a golf club head that shows a cavity pad and a slight concave shaped perimeter weight;

FIG. 9 illustrates an angled, side perspective view of a golf club head that shows a cavity pad and a perimeter weight;

FIG. 10 illustrates an angled, rear perspective view of a golf club head that shows a badge within a cavity pad; and, FIG. 11 illustrates a rear perspective view of a golf club head that shows a badge within a cavity pad.

The broken, dashed lines shown in the various figures depicting embodiments of the invention are included for the purpose of illustrating environment and do not form any part of the claimed design.
